DIE FOR STAMPING TAPERED TUBIFORM ELEMENTS

Kenneth T. Norris, Los Angeles, Calif.

Application February 11, 1938, Serial No. 190,025

8 Claims. (Cl. 113—42)

The present invention relates to and has for an object the provision of a new and efficient die for stamping tapered tubiform elements such as collars, sleeves, bands, rings, cylinders and the like, from sheet metal stock and also resides in the provision of a new and improved compound die with which the method hereof and other advantageous operations may be carried out with a saving in time, material and costs, and an accurate uniformity in the finished products.

One of the objects of this invention is to provide a die of the character described, by means of which sheet metal stock is blanked, drawn, pierced, and then drawn to final shape in one continuous operation, to form tapered tubular members or what may be termed tapered hollow cylinders, characterized by dimensional and shape uniformity and surface smoothness and adapted for various uses, for example, the construction of collapsible tubular bodies in the manufacture of drinking cups, pouring spouts and the like.

Another object of this invention is to provide a die structure such as described, wherein the taper given the work during the stamping operation sets up work holding forces which effectively prevent slipping or other movement of the work relative to certain elements of the die and thereby insure dimensional and taper uniformity in the finished products.

A further object is to provide a compound die of the character described wherein a die element thereof which moves with the work to effect the drawing thereof to final form, is provided with a work engaging face formed or treated to effectively prevent movement of the work relative to said face during said final operation.

I have shown a preferred embodiment of my improvements in the accompanying drawing, subject to modification, within the scope of the appended claims, without departing from the spirit of my invention.

Fig. 1 represents a vertical sectional view of a die constructed in accordance with this invention and showing the elements in normal position as before starting a stamping operation;

Fig. 2 represents a cross sectional view taken on the plane of line 2—2 of Fig. 1;

Fig. 3 represents an enlarged fragmentary vertical sectional view taken through the die showing the position of parts thereof during the first stage of operation as when drawing the stock, the die elements having traveled through approximately one-half of the full stroke thereof;

Fig. 4 represents an enlarged fragmentary vertical

sectional view of the die, as when the piercing operation has been completed, following the operation shown in Fig. 3 and before the final drawing operation;

Fig. 5 represents an enlarged fragmentary sectional view showing the die elements and the work as when the stamping operation has been completed;

Fig. 6 represents a perspective view of the blank;

Fig. 7 represents a perspective view of the product as when the first drawing operation has been completed;

Fig. 8 represents a perspective view of the product as when the piercing operation has been completed;

Fig. 9 represents a perspective view of the finished product which has been drawn to final shape from the form, as indicated in Fig. 8.

In carrying out the method of this invention to produce in one continuous stamping operation from sheet stock, a tapered tubiform member, the stock is first blanked, then drawn into the form of a tapered inverted cup, then pierced and finally again drawn to produce a tapered cylinder free from flanges or irregular formations at the edges and fully open at its ends. Heretofore it has been the practice in making tapered tubiform members to first blank and draw the stock in the form of a cup in one operation, and then as a separate operation, pierce the cup. Such methods required the use of separate dies and presses. With the method of this invention but one die unit is used and the four operations are continuous and are respectively: blanking, drawing, piercing and drawing. The first drawing operation produces a partially formed tapered member like an inverted cup, having a closure wall at its upper end and immediately that this is formed, the piercing operation takes place, so as to remove all of said closure except a small inwardly extending annular flange, and the final operation draws the work so as to draw or straighten out the flange and lengthen the tubiform element to its completed form, as shown in Fig. 9. Under this method the taper which has been formed in the work up to the time that the punching operation has been completed and the final drawing operation commences, is an important factor in that it sets up work holding forces preventing relative movement between the work and the movable die elements during said final drawing operation, it being noted that if the work is permitted to move relative to said die

elements, an error as to the dimensional characteristics of the finished products will take place, and it will be impossible to obtain uniformity in the finished products. The method further contemplates the step of creating a pronounced work holding force effected thru the movable element of the die against the work during the final drawing operation and the completion of the product, this force being substantially nil or ineffective during the other stages of operation of the die. The creation or application of this force as aforesaid, will insure the movement of the movable die element and the work as one and positively prevent relative movement between the work and said element during the final operation, although primarily the taper in the work, especially when pronounced, will prevent such relative movement and insure uniformity in the finished products.

I have provided a compound die with which the methods of this invention and other methods may be carried out in a particularly efficacious manner. As here shown this compound die primarily comprises a movable compound die element A and a stationary compound die element B. The movable die element A primarily includes a holder 1 secured by a clamp 2 to a press, not shown, a tubular punch and die member 3 fixed in any suitable manner to said holder, and a piercing punch 4 fixed to said holder and extending into the bore of the tubular punch and die member 3. Surrounding the piercing punch 4 and having a working fit in the bore of the member 3 is a knock-out sleeve 5 for ejecting the finished work from said member 3. This sleeve 5 is operated to eject the work by means of a plunger 6 arranged in the holder 1 to depress pins 7 resting on an annular flange 8 of said sleeve. This flange is movable in a counterbore 9 of the tubular member 3. The plunger 6 is actuated by suitable elements of the press, not shown, which elements are a part of the usual press means for moving the die element A as a whole into and out of operative relation to the stationary die element B as is customary in the art. The tubular compound punch and die element 3 has an outer edge serving as a blanking punch 10 and an inner die face 11 serving as a drawing die. This face or drawing die 11 is tapered and preferably constructed, formed, or treated to positively hold the blank from slipping or otherwise moving relative thereto, as will be hereinafter more fully described. One way of preventing the blank or work from slipping is to form, as here shown, a series of annular ribs and grooves as indicated by the numeral 12, whereby a serrated or roughened die face is provided for effectively gripping and holding the work.

The compound and stationary die element B generally includes a die block 13 secured to the bed of the press, not shown, by means of a holder 14; a blanking die 15 fixed in said block, and a tubular piercing and forming die 16 fixed to said holder and extending into said blanking die so as to define an annular space between opposed portions of the die and punch. A blank holding sleeve 17 is reciprocally mounted in said annular space and has a working fit with the piercing and forming die 16 and the blanking die 15. This blank holding sleeve 17 is spring loaded and thereby yieldingly held in position to cooperate with the tubular punch 3 for holding the blank during the initial stages of the stamping operation. As here shown, suitable spring means 18

on the holder 14 operate thru a pin 19 to yieldingly support the sleeve 17.

In the operation of the compound die of this invention, as the movable element A thereof is moved to cooperate with the stationary element B, the punch 3 engages the sheet metal or other sheet stock lying on the blanking die 15 and thereby cuts out a circular imperforate blank C, as shown in Fig. 6.

As the blank holder 17 is normally disposed 10 with its outer end spaced slightly inwardly of the plane of the outer face of the blanking die, the blank is gripped between the lower end of the punch 3 and said holder immediately following the blanking operation. At substantially the 15 same time that the blank holder and punch 3 grip the blank, the initial drawing operation of the blank commences, inasmuch as the annular marginal portion D of the blank then engaged between said blank holder and said punch will be 20 drawn downwardly, as indicated in Fig. 3, relative to the central body E of the blank, which latter is then supported by and extends over the outer end of the piercing and forming die 16. It should be noted that the outer end of the die 16 is slightly inwardly spaced from the outer face of the holder 17, whereby to allow for gripping of the blank in advance of the start of the first drawing operation. As this initial drawing operation takes place, the outer face of die 16 and die face 11 cooperate to form a tapered circular portion F (see Fig. 3) defined between the marginal portion D and the body E, and as the drawing operation continues the circular portion F is 25 lengthened and the marginal portion D is reduced in width. The outer face of the piercing and forming die 16 is tapered as at 29, corresponding to the taper of the die 11, and the outer end edge of said die is rounded as at 21, to accommodate the drawing of the blank as aforesaid. 30

As the drawing operation progresses from the stage, as shown in Fig. 3, the blank is drawn to the form of an inverted cup, as shown in Fig. 7. At substantially the same time that the blank has been drawn to the form of an inverted cup, as shown in Fig. 3, and before the final drawing operation which produces the finished work shown in Fig. 9, the die elements A and B cooperate to produce a tubiform member, as shown in Fig. 4, this being the third operation effected in the progressive thrust of the punch and die element A. Referring more specifically to this third or piercing operation it is seen that just before the blank takes the form of an inverted cup, as shown in Fig. 7, the sleeve 5 being extended beyond the punch 4, will engage the marginal portion of the body E of the blank and there come to rest so that substantially at the time the blank assumes the finished cup form, the punch 4 will engage said body and then cooperate with the piercing and forming die 16 to cut out said body except for an annular inwardly extending portion G, as shown in Fig. 8. The slug thus cut will drop thru the punching die 16 and a contiguous slug tube 22 fixed to the holder 14. 45

The die element A continues its thrust of the punch and die member 3 after the piercing operation, this movement of said member having been continuous from the start of the stamping operation, and the final operation of drawing the blank to the finished form is then effected. With reference to Fig. 4, wherein the elements of the die are shown in the position assumed when a 50

piercing operation has been completed, it is seen that the flange portion G of the blank lies upon the rounded upper end 21 of the die 16 and the circular tapered part of the blank F is engaged between the tapered faces 11 and 20 of the drawing die and said die 16. At this time the upper part of the inner face of the portion F engages the upper part only of the face 20 and the lower part of said inner face is spaced clear of the lower part of the said face 20, as shown in Fig. 4, whereas the outer face of the portion F is closely engaged with the die face 11 except at the upper portion thereof where clearance is provided as shown in Fig. 4. These clearances are necessary to effect the continuous drawing of the blank during the continuous movement of the member 3 and preliminary to the final drawing operation. With the parts in the positions shown in Fig. 4, further travel of the member 3 will cause the blank to be moved bodily with the member 3 along the tapered face 20 of the piercing and forming die 16 and the flange portion G will be drawn downwardly between the faces 11 and 20 and become smoothed out as a part and continuation 25 of the annular wall F. The rounded end 21 permits of the smooth drawing of the flange G, as aforesaid. The die elements A and B are then separated as is customary in the art, and the knock-out sleeve is actuated by the press operated plunger 6 thru the pin 7 to be depressed and thereby push out the finished product. This product is smooth and substantially free from die marks and takes the form of a finished smooth-edged tapered tube or sleeve which is 35 fully open and free from flanges at its ends and subject to many uses as aforesaid.

It should be noted that the method and die apparatus of this invention provide for a continuous movement of the die elements while the 40 four stages of operation take place, said stages being the blanking, initial drawing, piercing and final drawing of the work to finished form.

In accordance with this invention, throughout the time the blank is being drawn into the form 45 of the inverted cup, as shown in Fig. 7, the die member 3 is moved relative to the body of the blank as the latter is then held by the upper end of the piercing and forming die 16. At the completion of this drawing operation the portion D 50 of the blank is drawn from between the ends of the die member 3 and holder 17 up into the die, into substantially the position shown in Fig. 4 and is then in such engagement with the die face 11 that when the piercing operation takes place, the die and blank will move bodily as one, relative 55 to the piercing and forming die 16, whereby to draw the blank into the finished tubular form free from end flanges or irregularities and fully open at its ends. If the die face 11 is ribbed, as at 12, or otherwise roughened, the blank will be more effectively held against movement relative to said die face.

It will be seen that with the method and means 60 of the invention a die stamping operation may be efficaciously carried out to produce tapered tubiform members of uniform dimensions and in finished form at a lower cost as to equipment, time and labor, than has been possible heretofore. While the die equipment here shown is designed 65 for producing tapered tubiform elements of circular form, it is to be understood that it is within the scope of this invention to produce tapered tubiform elements of oval rectilinear or other 70 shapes as desired, under the method, and with 75

the structural features and arrangements hereof.

I claim:

1. A compound die for producing tapered tubiform elements from sheet stock in one continuous operation, including cooperating die devices, one 5 of which is movable relative to the other for drawing a blank of sheet material to produce a cup-shaped member fully open and free of flanges at one end and closed at its other end, means included in said devices and operating to remove 10 the central portion of the closed end and leave a flange and means embodied in said device whereby continuation of the relative movement of said die devices will straighten out said flange and produce a tubiform element fully open and 15 free of flanges at its ends.

2. A compound die for producing tapered tubiform elements from sheet stock in one continuous operation, including a stationary die device, a continuously movable die device cooperating with 20 the stationary device during its movement, for continuously drawing a blank of sheet material into tapered form, having one end closed and the other fully open and free of flanges, means included in said devices and operating automatically 25 for piercing the closed end of the blank and removing a portion thereof so that a flange remains, and means embodied in said devices whereby continuation of the drawing operation will straighten out said flange to form one end 30 portion of the finished element.

3. A compound die for producing tapered tubiform elements from sheet stock in one continuous operation, including a stationary die device, a continuously movable die device cooperating 35 with the stationary device during its movement, for drawing a blank of sheet material into tapered form wherein one end of the form is free of flanges and open and the other end is closed, means included in said devices and operating automatically 40 for piercing the closed end of the blank and removing a portion thereof so that a flange remains, and means embodied in said devices whereby a continued movement of said movable die device will draw said flange into position 45 to form a tapered tubiform end portion of the finished element, said movable die device including a tapered die face for engaging and bodily moving the blank during the drawing operation which straightens out said flange. 50

4. A compound die for producing tapered tubiform elements from sheet stock in one continuous operation, including a stationary die device, a continuously movable die device cooperating with the stationary device during its movement, for 55 drawing a blank of sheet material into tapered form having one end fully open and free of flanges and the other end closed, means included in said devices and operating automatically for piercing the closed end of the blank and leaving 60 a flange, and means embodied in said devices, whereby a continuation of the drawing operation will straighten out said flange at one end of a tapered tubiform element fully open and free of flanges at both ends, said movable die 65 device including a tapered die face for engaging the tapered portion of the blank and bodily moving the blank throughout the drawing operation which follows said piercing operation.

5. A compound die for producing tapered tubiform elements from sheet stock in one continuous operation, including a stationary die device, a continuous movable die device cooperating with the stationary device during its movement, for 70 drawing a blank of sheet material into tapered 75

form wherein one end is free of flanges and fully open and the other end is closed, means included in said devices and operating automatically for piercing the closed end of the form so that a flange is left, and means embodied in said devices whereby a continuation of the drawing operation will straighten out said flange and produce a tapered tubiform element fully open at both ends, said movable die device including a 5 tapered die face for engaging the tapered portion of the blank and bodily moving the blank throughout the drawing operation which follows said piercing operation, said face being roughened to provide a gripping surface to prevent movement of the blank relative thereto during said 10 final drawing operation.

6. A compound die for producing tapered tubiform elements from sheet stock in one continuous operation, including a stationary die device, a 20 continuously movable die device cooperating with the stationary device during its movement, for drawing a blank of sheet material into tapered form free of flanges at one end, means included in said devices and operating automatically for 25 piercing the other end of said form so as to produce a flanged open end therefor and means embodied in said devices whereby a continuation of the drawing operation will straighten out said flanged end and produce a tapered tubiform element 30 fully open at both ends, said movable die device including a tapered die face for engaging the tapered portion of the blank and bodily moving the blank throughout the drawing operation which follows said piercing operation, said face 35 being provided with a series of ribs and grooves to prevent movement of the blank relative thereto during said final drawing operation.

7. A compound die for producing a tapered tubiform element from sheet stock in one continuous 40 operation, including a blanking die, a piercing and forming die located within and circumferentially spaced from the blanking die, a punch

and die member having a tapered die face and a 5 punching edge at one end and adapted to be continuously moved in the space between said blanking and piercing dies while engaged with the blank, said piercing and forming die having a tapered outer face, between which and said tapered die face, the blank is drawn into tapered tube free of flanges and fully open at one end and closed at its other end and a piercing punch operating in the punch and die member, to pierce 10 the blank and thereby open said closed end save for an inwardly extending flange, said blank and said punch and die member moving bodily relative to said piercing and forming die following said piercing operation, to straighten out said 15 flange and thereby produce a tapered tube free of flanges at both ends.

8. A compound die for producing a tapered tubiform element from sheet stock in one continuous 20 operation, including a blanking die, a piercing and forming die located within and circumferentially spaced from the blanking die, a punch and die member having a tapered die face and a 25 punching edge at one end and adapted to be continuously moved in the space between said blanking and piercing dies while engaged with the blank, said piercing and forming die having a tapered outer face, between which and said tapered die face, the blank is continuously drawn 30 into tapered form, and a piercing punch operating in the punch and die member to pierce the blank and thereby render the same tubular with a flange at one end, said blank and said punch and die member moving bodily relative to said 35 piercing and forming die following said piercing operation, to straighten out said flange draw the blank into tapered and tubular form free of flanges at both ends, said die face being ribbed to prevent movement of the blank relative thereto during said final drawing operation. 40

KENNETH T. NORRIS.
